ATTORNEY.

UNITED STATES PATENT OFFICE.

JOHN W. UDALL, OF WESTON, ONTARIO, CANADA.

PERSONAL SAFETY APPLIANCE.

1,315,436.

Specification of Letters Patent. Patented Sept. 9, 1919.

Application filed February 17, 1919. Serial No. 277,561.

To all whom it may concern:

Be it known that I, JOHN W. UDALL, a subject of the King of Great Britain, residing at Weston, in the Province of Ontario and Dominion of Canada, have invented certain new and useful Improvements in Personal Safety Appliances, of which the following is a specification.

The primary object of this invention is to prevent injury to persons from falling from an elevated position or from a moving vehicle and is more particularly adapted for use upon public carriers such as street cars to prevent the conductor from falling or being thrown from the car in the discharge of his duty in the collection of fares which necessitates the use of both hands and thereby increases the chances of the conductor being thrown from the car by a sudden jerk or when entering a curve.

In accordance with the invention a suitable hanger is connected with the body preferably by means of a harness and the opposite end of said hanger is connected with the carriage mounted to travel upon an overhead track, the parts being so disposed that in the event of the conductor or other person losing his balance and tending to be precipitated to the ground the attachment will come into play to prevent such catastrophe and obviate any fatality from such cause.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the drawing hereto attached,

Figure 1 is a perspective view of part of a street car showing the application of the invention.

Fig. 2 is a front view of the body harness showing the same applied.

Fig. 3 is a detail view of the body harness extended.

Fig. 4 is a sectional detail of the overhead tracks showing the carriage mounted thereon and the upper portion of the hanger connected with the carriage.

Corresponding and like parts are referred to in the following description and indicated in the several views of the drawing by like reference characters.

The numeral 1 designates an overhead track which extends along the sides of a railway car and 2 is a carriage mounted to travel on said track. These parts may be of any construction. The overhead track 1 extends in the same general direction as the running board 3 along which the conductor moves when collecting the fares during a trip. The track 1 is of the slotted type, and the carriage 2 comprises a body, having a depending portion extending through the slot of the track, and side wheels to travel on the parts of the track at the sides of the slot.

A suitable harness is provided to be applied to the torso or body portion of the conductor or other person to be safeguarded. This harness in the preferable construction embodies a waist belt and shoulder straps, the waist belt being shown as comprising two straps 4 and 5 and the shoulder straps being indicated at 6 and connected to the straps 4 and 5. The shoulder straps 6 have their front portions connected to end portions of the straps 4 and 5 and the rear portions of the shoulder straps merge into a single strap which is centrally disposed in the back and is connected centrally to the straps 4 and 5. When the body harness is in position the straps 4 and 5 pass about the body and are buckled in front, as indicated most clearly in Fig. 2. The shoulder straps occupy a relative position substantially in a manner similar to suspenders and are provided at their upper ends with loops 7 which are adapted to be engaged by means of short straps 8. Fig. 1.

The hanger consists of a strap 9 which is connected at its lower end to the harness and at its upper end to the carriage 2. This strap is adapted to be lengthened or shortened in any usual way to adapt the device to persons of different heights. A loop 10 is provided at the back of the harness and at the juncture of the shoulder and upper waist straps and the lower end of the hanger 9 is connected thereto. In this manner the hanger 9 is disposed in the back of the person and is out of the way.

In practice the harness is applied to the body of the person and the hanger is attached thereto and connected with the overhead support such as the traveling carriage 2. In the application of the invention to a street railway car provided along its sides

with running boards the upper end of the hanger 9 is connected to the carriage 2 mounted to travel upon the overhead track 1. It will be readily understood that the conductor moving along the running board 3 may with reasonable safety use both hands in the collection of fares making change and punching trip slips or attending to other duties without fear of serious mishap by 10 falling or being thrown from the car because the safety appliance will prevent his falling to the ground. The carriage provided for the free movement of the conductor along the running board and the hanger 9 being in the back does not interfere with or incommode the conductor in attending to the usual duties.

20 The foregoing description and the drawings have reference to what may be considered the preferred, or approved form of my invention. It is to be understood that I may make such changes in construction and arrangement and combination of parts, materials, dimensions, et cetera, as may prove 25 expedient and fall within the scope of the appended claims.

Having thus fully described my inven-

tion, what I claim as new and desire to secure by Letters Patent is:—

1. A vehicle provided with a running board, and having an overhead track paralleling the running board, a harness adapted to be applied to a person mounted upon the running board and a hanger connecting the harness with a carriage mounted upon the overhead track, the part being disposed to prevent the person from falling to the ground when losing his balance or being thrown from the running board.

2. A vehicle provided with a running board, and a paralleling overhead track, a carriage mounted upon the track to travel thereon, the running board forming a support for a person, a harness applied to the person on the running board and a hanger connecting the harness with the carriage to prevent the person falling to the ground when displaced from the running board.

In testimony whereof I affix my signature in presence of two witnesses.

JOHN W. UDALL.
